UNITED STATES PATENT OFFICE.

JOHN T. MEATS, OF TAUNTON, MASSACHUSETTS, ASSIGNOR TO MASON MACHINE WORKS, OF TAUNTON, MASSACHUSETTS, A CORPORATION OF MASSACHUSETTS.

PICKING MECHANISM FOR LOOMS.

SPECIFICATION forming part of Letters Patent No. 729,626, dated June 2, 1903.

Original application filed June 28, 1902, Serial No. 113,672. Divided and this application filed November 1, 1902. Serial No. 129,686. (No model.)

To all whom it may concern:

Be it known that I, JOHN T. MEATS, a citizen of the United States, residing at Taunton, in the county of Bristol and State of Massachusetts, have invented an Improvement in Picking Mechanism for Looms, of which the following description, in connection with the accompanying drawings, is a specification, like characters on the drawings representing like parts.

This invention relates to looms, and more particularly to the picking mechanism thereof; and it has for its object the improvement in the operation of such mechanism and simplification and cheapening of the construction of the same.

This application is a division of an application, Serial No. 113,672, filed by me on the 28th day of June, 1902, in which the picking mechanism forming the subject-matter of this application is shown and described, but not claimed.

The picking mechanism of my present invention relates more especially to that type wherein the picking-shaft and ball or roll, which receive their motion from the usual picking-cam, are placed below the latter to avoid throwing oil upward against the warps.

Various means have been heretofore used to hold the ball or roll in contact with the picking-cam—such, for instance, as a tension-spring attached by a hook at one end to the picking-shaft and hooked at its other end to a fixed part of the loom. So, too, the picking-shaft has been surrounded by a spring connected at one end to the shaft and fixedly held at its other end. In practice these structures have been found to be lacking in reliability, and they are also open to other objections, and one part of my invention has for its object the production of simple and effective means for overcoming these objections.

The novel features of my invention will be fully described herein, and particularly pointed out in the following claims.

Figure 1 is a right-hand-side elevation of a sufficient portion of a loom of usual construction to be understood with one embodiment

of my invention applied thereto; and Fig. 2 is a front elevation, partly broken out, of the mechanism illustrated in Fig. 1.

The loom side 1, crank-shaft 2, having fast and loose pulleys 3, 4 thereon, the lay 5, lay-sword 6, Fig. 1, secured at its lower end to the rock-shaft 7, the cam-shaft 8, having the picking-cam 9 fast thereon, the filling-fork 10, weft-hammer 11, breast-bearer 12, and the holding-plate 13, having the shouldered notch 14 for the shipper, may be and are all of usual or well-known construction and operate in well-known manner.

Bearings 30 on the loom side support the picking-shaft 31, mounted to rock therein and having an upturned arm 32, (shown as integral with the picking-shaft,) said arm being connected with the picker-stick 33 by a strap or other usual connecting device 34, the picker-stick being mounted on the rock-shaft 7 in usual manner and drawn back by the usual spring 35, Figs. 1 and 2.

A short arm 36 on the picking-shaft near its rear end has mounted upon it the picking-roll 37, extended beneath and coöperating with the periphery of the picking-cam 9, the rotation of the latter controlling the operation of the picker-stick by or through the rock-ing movement of the picking-shaft 31.

The front one of the picking-shaft bearings 30 is cast with a rearward extension 38 above the picking-shaft and provided with a recess or pocket 39, in which is seated one end of a coiled compression-spring, the other end of the spring being seated in a pocket 40 in the end of a short upturned arm 41, fast on 85 or integral with the picking-shaft. By this construction I am able to use a spring which is always in compression, (the spring keeping the roll 37 in engagement with the picking-cam 9,) such a spring being inexpensive to make, and in practice I have found it to give better results and to last much longer without permanent set than is the case with tension-springs of various kinds. Preferably the pocketed extension 38 is made as an integral part of the bearing-casting, and the arms 36, 32, and 41 are preferably made integral with the picking-shaft.

The construction herein described imparts a greater smoothness and uniformity to the picking motion and is not liable to get out of order or to deteriorate with use.

5 Having described my invention, what I claim as new, and desire to secure by Letters Patent, is—

1. In a loom, the picking-cam, a picking-shaft mounted in fixed bearings below the 10 picking-cam and having an arm, a roll on said arm to coöperate with the cam, a second, upturned arm on said picking-shaft having a pocket, a fixed pocket opposed thereto, and a compression-spring seated at its ends in the 15 said pockets and operating to maintain the roll in coöoperative engagement with the picking-cam.
2. In a loom, the picking-cam, a picking-

shaft mounted in right angles to the axis of rotation of the cam, fixed bearings for said 20 shaft, one of the bearings having an extension provided with a pocket, a roll carried by the picking-shaft and engaged by the cam, a second arm on said shaft, upturned and provided with a pocket facing the pocket in the extension, and a compression-spring seated at its ends in the pockets, to maintain the roll lifted in coöoperative engagement with the cam. 25

In testimony whereof I have signed my name to this specification in the presence of 30 two subscribing witnesses.

JOHN T. MEATS.
